CLAIM

The ornamental design for a table base leg stretcher, as shown
and described.

DESCRIPTION

FIG. 1 is a front elevational view of a table base leg stretcher
showing my new design, with the rear elevational view
thereof being identical.

FIG. 2 is a right-side elevational view thereof, with the left-
side elevational view thereof being a mirror image; and,

FIG. 3 is a top plan view thereof, with the bottom plan view
thereof being identical.

1 Claim, 1 Drawing Sheet

FIG. 1

FIG. 2

FIG. 3
